Patented Dec. 2, 1913.

UNITED STATES PATENT OFFICE.

NICHOLAS FRIEBAND, OF SHENANDOAH, PENNSYLVANIA.

MINER'S LAMP-HOLDER.

1,080,434.

Specification of Letters Patent.

Patented Dec. 2, 1913.

Application filed May 10, 1913. Serial No. 766,783.

To all whom it may concern:

Be it known that I, NICHOLAS FRIEBAND, a citizen of the United States, and a resident of Shenandoah, in the county of Schuylkill and State of Pennsylvania, have invented a new and Improved Miner's Lamp-Holder, of which the following is a full, clear, and exact description.

This invention relates to miners' equipment and has particular reference to an improved form of holder or bracket designed as a permanent attachment to a miner's cap for the purpose of detachably holding a well known type of oil lamp.

Among the specific objects of this invention is to simplify and improve this type of devices whereby they are cheaper, stronger and better adapted for their purpose than other devices now commonly used.

The foregoing and other objects of this invention will hereinafter be more fully described and claimed and illustrated in the drawings forming a part of this specification in which like characters of reference indicate corresponding parts in all the views, and in which—

Figure 1 is a vertical longitudinal section of a conventional form of cap having my improvement attached thereto and showing in elevation a miner's lamp supported in place; Fig. 2 is a view corresponding to Fig. 1 but indicating the position which is automatically assumed by the lamp when the cap is tilted forwardly; Fig. 3 is a front elevation; and Fig. 4 is a view of the blank from which the support is made, the scale being smaller than in the other figures.

Referring to the drawings for a more specific description of the invention, I show a cap comprising a crown 10, a sweatband 11 and a vizor 12. These parts are or may be of any well known or approved design or construction and assembled in any suitable manner.

The support or holder 13 comprises a substantially rectangular strip of material of any suitable nature, but preferably of a good quality of leather. This member is preferably formed or cut as indicated in Fig. 4 and provided with a plurality of holes 14 at its upper end 15 through which it may be connected to the top of the crown as by rivets 16. At the lower end 17 are formed holes 18 for securing the holder in any suitable position preferably to the vizor by rivets 19. It will appear, therefore, that

the upper and lower ends 15 and 17 are each bent at an angle to the main portion of the holder; otherwise, the holder is substantially rigid and stiff.

In this art it is desirable for the lamp, indicated at L, and provided with a supporting hook l, to be so supported upon the cap as to be prevented from lateral oscillations or movements and yet be permitted to gravitate freely with respect to the vertical longitudinal plane of the cap and its wearer. In other words, as indicated in Fig. 2, when the miner stoops and tilts his cap forwardly, the lamp should swing freely so that it will be relatively spaced from the vizor of the cap and therefore maintained in a substantially vertical upright position to avoid spilling of the oil and interference with the proper action of the lamp. To meet this requirement, therefore, in a practical and reliable manner, constructing the holder of leather, I form therein a tongue 20 having its upper end integral with the main portion of the holder and having its lower or free end 21 folded rearwardly and upwardly against the under surface of the end 15 and there secured as by a rivet 22 passing through holes 23 and 24. In the cutting of the blank, as shown in Fig. 4 I provide a slot 25 adjacent the upper end of the tongue 20, the slot being arranged with its longer axis coinciding with the axis of the tongue and having its lower end extended into the tongue or beyond the point of attachment between the tongue and the main part of the holder, thus providing a pair of comparatively flexible strips 26. These strips facilitate the aforesaid folding of the tongue, and after the folding is effected they constitute spaced forwardly projecting shoulders. The width of the slot 25 corresponds substantially to the thickness of the hook l of the lamp. Just in the rear of said shoulders 26 is formed a hole 27 through the tongue which also is of a diameter substantially equivalent to the diameter or thickness of the hook. This hole 27 receives the end of the hook, as shown in Fig. 1, and the looped portion of the hook is supported within the slot 25 and hence upon that portion of the tongue between the slot and the hole 27 and between the shoulders 26. It will follow, therefore, that since the hook has constant engagement in the hole 27, the lamp is prevented from swinging laterally around the axis of the hole 27 or from oscillating to

the right or left to any great extent. While the miner is working, however, the lamp, by means of the connection above described, is free to swing forwardly relatively to the cap 5 or automatically maintain its upright position at all times. The space or opening 28 formed by cutting out the tongue 20 is long enough to provide a clearance for the point of the hook when the lamp swings forwardly, but when the cap is elevated to an upright position the wall at the end of said opening serves as a support for the lamp.

It will thus appear that I provide a simple, cheap and effective lamp holder and 15 one which will thoroughly prevent any oil which might leak from the lamp to come into direct contact with the crown or sweat-band of the cap.

Having thus described my invention, I 20 claim as new and desire to secure by Letters Patent:

1. The combination with a miner's cap having a crown and a vizor, of a lamp holder constructed of one piece of flexible 25 material, means to secure the upper and lower ends of said holder to the crown and vizor respectively the intermediate portion of the holder being spaced from the crown, and said intermediate portion being slotted 30 to form a tongue having its upper end left integral with the main portion of the holder,

the free end of the tongue being bent rearwardly and upwardly against the upper portion of the holder and formed with a hole therethrough, and a slot being formed 35 in the holder adjacent the upper end of the tongue and in axial alinement therewith, said slot forming a pair of spaced shoulders in front of the tongue hole, substantially as and for the purposes set forth. 40

2. The herein described blank for a miner's lamp holder comprising a substantially rectangular single strip of material, said blank being formed with attachment holes at its opposite ends, the intermediate portion thereof being slotted to form a tongue having its upper end left integral with the holder and its free end provided with a central hole, and a slot being formed through 45 the holder in axial alinement with said tongue and its hole, said slot extending across the point of attachment between the tongue and the main portion of the holder, substantially as set forth.

In testimony whereof I have signed my 50 name to this specification in the presence of two subscribing witnesses.

NICHOLAS FRIEBAND.
